Primary Examiner — Darlington Ly(74) *Attorney, Agent, or Firm* — Gerald E. Hespis;
 Michael J. Porco; Matthew T. Hespis(57) **CLAIM**

The ornamental design for a rotary cutting tool, as shown and described.

DESCRIPTION

FIG. 1 is a perspective view of a rotary cutting tool in accordance with my design;

FIG. 2 is a top plan view of the rotary cutting tool of FIG. 1;

FIG. 3 is a bottom plan view thereof;

FIG. 4 is a side elevational view thereof taken from the right side of FIG. 1;

FIG. 5 is a side elevational view thereof taken from the left side of FIG. 1;

FIG. 6 is a front elevational view thereof; and,

FIG. 7 is a rear elevational view thereof.

The broken lines in FIGS. 1-3 illustrate portions of the rotary cutting tool and form no part of the claimed design.
